CRACKING HYDROCARBON OIL

Joseph K. Roberts, Flossmoor, and Morris T. Carpenter, Chicago, Ill., assignors to Standard Oil Company, Chicago, Ill., a corporation of Indiana

Application July 16, 1938, Serial No. 219,566

15 Claims. (CL 196—48)

This invention relates to a combination cracking and coking process adapted for the treatment of hydrocarbon oil to produce maximum yields of gasoline or motor fuel of superior anti-knock quality.

The invention contemplates a process in which raw charging stock, such as topped or reduced crude petroleum is subjected to coking, the evolved vapors fractionated to separate a heavy condensate from lighter fractions, the heavy condensate subjected to cracking primarily to effect conversion into a large yield of intermediate constituents adapted for subsequent conversion into gasoline, the cracked vapors subjected to fractionation together with the vapors from the coking operation so as thus to accumulate in such lighter fractions constituents adapted for high cracking per pass cracking and finally the cracking of such lighter fractions in a separate cracking zone to effect conversion into high anti-knock constituents.

When it is sought to coke a cracked residue, particularly when the cracked residue is a product of a more or less drastic cracking operation, the conversion into the coke residue is accomplished with a large yield of coke and a small yield of gasoline, and such a coking operation is accompanied with a relatively large yield of gas per unit volume of gasoline or light distillate produced, as compared with the yield of gas produced in the coking of a virgin stock such as topped or reduced crude. Furthermore, the subjection of the cracked residue to coking results in the loss of constituents highly valuable for use as fuel oil. The cracked residue possesses a higher specific gravity for a given viscosity than topped or reduced crude and a consequent higher calorific value. Accordingly, in the practice of our invention, the coking operation is applied to the virgin stock, the topped or reduced crude, to convert immediately the virgin stock to ultimate yields of volatilized products, including not only gasoline but intermediate constituents adapted for high cracking per pass conversion into gasoline, as well as certain heavier constituents which are separately cracked to produce an additional yield of intermediate constituents. The cracked residue derived from the cracking of the intermediate constituents is segregated for the production of fuel oil. In practicing the invention the intermediate constituents are subjected to a high cracking per pass cracking operation, the resultant cracked products separated into vapors and cracked residue, and the cracked residue flash-distilled in contact with the cracked

products produced in the cracking of the heavy condensate obtained in the fractionation of the evolved vapors from the coking operation, while lighter fractions, obtained in this fractionation from both the coking operation and from the cracking of the heavy condensate, constitute the constituents that are passed to the high cracking per pass cracking operation.

The invention further contemplates a method 10 of processing crude petroleum to accomplish maximum yields of gasoline or motor fuel of superior anti-knock quality. In accordance with the invention the crude oil is fractionated to form a topped or reduced crude and a condensate such as gas oil. The topped or reduced crude is subjected to coking for immediate conversion into an ultimate yield of volatile products and the condensate fraction is subjected to high cracking per pass cracking for conversion into anti-knock gasoline. The products of the later cracking are separated into vapors and cracked residue and the cracked residue is passed to a flashing zone. In a preferred embodiment of the invention the topped or reduced crude is introduced into a 15 dephlegmator receiving vapors from the coking operation and the resultant combined reflux condensate and residual crude oil constituents are passed to the coking zone. The vapors are further fractionated to form a heavy condensate of 20 the nature of heavy gas oil, which is subjected to cracking in a heavy gas oil cracking zone and the resultant cracked products directed into the flash zone for separation into vapors and residue together with the cracked residue from the high 25 cracking per pass cracking operation. In fractionating the crude petroleum, it is advantageous to fractionate the vapors into a heavy gas oil fraction and a light gas oil fraction and the light gas oil fraction is, in accordance with the invention, 30 directed to the high cracking per pass cracking zone, while the heavy gas oil fraction is subjected to cracking in the heavy gas oil cracking zone. In accordance with the invention, the heavy gas oil fraction from the crude oil may 35 be refluxed in a fractionating zone in which combined vapors from the coking operation and the flashing operation as well as vapors from the heavy gas oil cracking operation are fractionated, heavier constituents in the vapors being collected 40 as a heavy gas oil condensate for cycling to the heavy gas oil cracking zone and lighter fractions being combined with the light gas oil from the crude oil distillation for cracking in the high cracking per pass cracking zone. An advantageous operation in accordance with the invention 45 50 55

is to direct lighter fractions, obtained in the fractionation of the combined vapors from the coking operation, the flashing operation and vapors from the heavy gas oil cracking operation, into a fractionator in which vapors from the high cracking per pass cracking operation are fractionated and to cycle the resultant reflux condensate to the high cracking per pass cracking zone.

An important feature of the invention is that vapors from the coking operation are fractionated at relatively high temperatures and under conditions of low pressure approaching atmospheric, or in fact even under sub-atmospheric pressure, and preferably with the aid of a stripping medium, such as steam or gas, in order to effect fractionation of extremely high-boiling constituents having boiling points within the cracking temperature range. In accordance with the invention the fractionation may be so conducted as to form a condensate, having an initial boiling point of upwards of 800° F. and preferably in excess of 850° F. (as determined by a vacuum distillation and interpolated to an atmospheric pressure basis), for cycling to the coking zone to be subjected to coking with the residual constituents of the crude petroleum. Thus, the topped or reduced crude may be introduced into a primary dephlegmating or fractionating zone to dephlegmorate the vapors from the coking zone, under such conditions of temperature and pressure that the reflux condensate contained in the resultant mixture of unvaporized crude residue and reflux condensate will consist essentially of constituents boiling from about 800° F. or from 850° F. up to and including the heaviest constituents present which may boil at about 900° F. or 1000° F. (such boiling points being determined by vacuum distillation and interpolated to an atmospheric pressure basis). By restricting the cycle stock to the coker to material of this extremely high boiling point, it is found that in the complete combination process the maximum ultimate yield of gasoline is produced. Furthermore, the ratio of liquid fuel yield to the yield of coke and gas is higher when subjecting to the coking operation only material boiling above about 800° F. The ratio of crude residue to cycle condensate is of the order of 4:1 or 4:2. After the dephlegmation or fractionation of the vapors in contact with the introduced topped or reduced crude, the vapors are further fractionated to form a fraction having an initial boiling point of about 650° F.-700° F. and having an end point of the order of 800° F. (as determined by a vacuum distillation and interpolated to an atmospheric pressure basis). This heavy fraction is directed to the heavy gas oil cracking zone and subjected to conversion into constituents of intermediate boiling points well adapted for treatment at high cracking per pass conditions for conversion into gasoline of high anti-knock quality.

An important object of our invention is to accomplish an effective cracking operation in which the oil is processed to ultimate yields with a minimum number of separate cracking operations without, however, sacrificing the yield of gasoline or the anti-knock quality thereof, or the on stream time of the unit.

For the purpose of more fully disclosing the invention reference will now be had to the accompanying drawing which is a flow diagram illustrating apparatus adapted for the practice of the invention.

In the apparatus illustrated the charging stock such as crude petroleum is charged by a pump 10 to a heat exchanger or exchangers indicated diagrammatically at 11, in which the charge may be preheated by heat exchange with hot products of the system. The preheated charge passes through transfer line 12 to a heating coil 13 located in a furnace or heating chamber 14 in which the charge may be heated to a desired distilling temperature. An outlet line 15 extends from the heating coil and is provided with branches 16 and 17. The branch 16 extends to a distilling and fractionating tower 18. A by-pass line 19 is provided for bypassing the heating coil 13 and for passing the preheated charging stock directly from heat exchanger 11 to the tower 18.

The tower 18 is provided with suitable fractionating elements such as bubble trays and with suitable refluxing means for accomplishing the desired fractionation therein. A steam line 20 is indicated for introducing steam into the tower to aid in stripping light ends from the tower bottoms. A plurality of trap-out trays such as 21, 22, 23 and 24 are provided with lines 25, 26, 27 and 28 extending from the trays, respectively. The overhead vapors pass to a condenser 29 and the distillate is collected in a receiver 30. In practice it is advisable to pass the several condensates collected in the trays 21, 22, 23 and 24 to side stripping towers in order to further fractionate the condensates and remove lighter constituents therefrom but for the purpose of simplicity the apparatus for stripping the several side cuts has been omitted from the drawing.

The coking unit of the process includes a heating coil 31 disposed in a suitable furnace or heating chamber 32 adapted to heat the oil to be coked to a temperature sufficient to accomplish coking and a coking drum 33 into which the heating coil discharges and in which the oil is held at a coking temperature to effect coking. In practice a plurality of coking chambers are provided so that continuity of the coking operation may be maintained in conjunction with the rest of the continuous process. Thus the stream from the heating coil 31 may discharge into one or more of the coking chambers while in other of the coking chambers the coke may be undergoing digestion for hardening and in other of the chambers removal of the coke may be taking place and thus a substantially continuous evolution of vapors from a chamber or chambers in which coking is taking place may be maintained. The vapors pass through a vapor line 34 to a dephlegmating tower 35. In the specific arrangement illustrated, the vapor line 34 is shown provided with branches 36 and 37 extending to the tower 35. The tower is equipped with suitable fractionating elements such as bubble trays, discs and doughnut trays or the like and with appropriate refluxing means for regulating the fractionation in the tower. A trap-out tray 38 is disposed beneath the branch vapor line 36 and another trap-out tray 39 is disposed beneath the branch vapor line 37. The lower section of the tower 35 includes a separating zone 40 for separating into vapors and liquid residue certain products as will be hereinafter explained. A drawoff line 41 is provided for removing the residue and a reflux line 42 is provided for introducing a refluxing medium to dephlegmorate the vapors evolved in the separating zone 40.

75 The topped or reduced crude is drawn from

the crude fractionating tower 18 by a pump 43 and line 44 shown with one branch line 45 extending to the transfer line 12 and another branch line 46 extending to the tower 35. In one method of operation the crude oil introduced by pump 10 is heated by heat exchange with hot products of the system in exchanger 11, passed thence through transfer line 12 to the heating coil 13, thence through line 15 and branch line 16 into the crude fractionating tower 18. The resultant residue is drawn from tower 18 by pump 43 and passed through lines 44 and 46 into the tower 35 above the trap-out tray 38. A steam line 47 is indicated for introducing steam into the trap-out tray to promote the stripping of the heavy crude residue.

In another method of operation contemplated by the invention the crude oil is heated to a moderate distilling temperature, as by heat exchange with hot products of the system in exchanger 11, and the preheated oil is passed hence through the line 19 into the tower 18. The topped crude is drawn from tower 18 by pump 43 and passed through lines 44 and 45 to the heating coil 13 wherein the residue is further heated, after which it is discharged through line 15 into branch line 17, which communicates with line 46 through which the residue is discharged into the tower 35.

In either of these methods of operation oil to be coked is drawn from trap-out tray 38 through line 48 and also, if desired, through a line 49 from trap-out tray 39, to a line 50 and is directed by pump 51 through line 52 to the heating coil 31. Thus topped or reduced crude, together with any reflux condensate that may collect with the residue in the pan 38, as well as any heavy reflux condensate collecting in pan 39, may be normally charged by the pump 51 to the heating coil 31 in which the oil is raised to a coking temperature for coking in the coking drum 33.

At certain times, particularly near the end of the coking operation in a given drum 33 and immediately prior to the switching over to another of the coking drums, the vapors from the coking drum may contain more or less entrained coky material or heavy material of a coke-forming nature, capable of causing coking difficulties in the heating coil 31 and at such times the vapors from the coking drum, instead of entering the tower 35 through line 36 or through both lines 36 and 37, are permitted to enter the tower only through the lower line 37, and with the valve in line 49 closed, the pump 51 takes suction through line 48 on the trap-out tray 38, while the dirty material collecting in tray 39 is either permitted to overflow into the separating zone 40 or is separately withdrawn from the tower through a line not shown.

Vapors from tower 35 pass through line 53 to a fractionating tower 54 which is provided with suitable fractionating elements such as bubble trays, disc and doughnut trays or the like, and with suitable refluxing means for controlling the fractionation therein. A steam line 55 is indicated for supplying steam for stripping the reflux condensate collecting in the lower part of the tower. Heavy reflux condensate withdrawn from trap-out tray 24 of the crude fractionating tower 18 through line 28 may be directed by pump 56 and line 57 into the tower 54. Reflux condensate is withdrawn from tower 54 by pump 58 and passed to a heating coil 59 positioned in furnace or heating chamber 60

in which the condensate is heated to a cracking temperature and the resultant products of cracking are passed through transfer line 61 to the separating section 40 of tower 35. The overhead vapors from tower 54 pass to a condenser 62 and the distillate is collected in a receiving drum 63.

To refer now to the apparatus for the high cracking per pass cracking operation, a pump 64 is provided with an intake line 65 manifold to the lines 25, 26 and 27, so that condensates from any or all of the trays 21, 22 and 23 of the crude fractionating tower 18 may be withdrawn by the pump and directed to a heating coil 66 positioned in a furnace or heating chamber 67 adapted for applying a high cracking temperature to the oil. The cracked products pass from the cracking coil 66 into a transfer line 68, into which a quenching stock may be introduced by line 69, and are discharged into a separator 70 wherein separation of vapors from liquid residue takes place. A reflux liquid may be introduced into the upper portion of separator 70 through a line 71 and the separator may be provided with suitable contacting or fractionating elements such as bubble trays, disc and doughnut trays and the like, so that the separated vapors may be given a preliminary dephlegmation before passing through a vapor line 72 to a fractionating tower 73. The tower 73 is provided with suitable fractionating elements such as bubble trays and the like, and with appropriate refluxing means for regulating the fractionation therein and accurately controlling the endpoint of the overhead fraction. The overhead vapors pass to a condenser 74 and the distillate is collected in the receiving drum or gas separator 75. Reflux condensate from the fractionating tower is cycled by pump 76 and line 77 to the heating coil 66.

Distillate from the receiving drum 63 is directed by pump 78 and line 79 to the tower 73 wherein the distillate is subjected to fractionation, the lighter constituents passing overhead to the condenser 74 and receiver 75 and the heavier constituents being combined with reflux condensate in the tower for cycling to the cracking coil 66.

The separated residue collecting in the tower 70 together with any included reflux condensate resulting from the dephlegmation of the vapors therein, is withdrawn through a pressure-reducing valve 80 and directed through line 81 into the separating section 40 of the tower 35 for flash-distillation therein.

Provision may be made in accordance with the invention for withdrawing a special cut or cuts from the tower 73 and for accomplishing the stripping or fractionation of the withdrawn cuts to produce a special product of desired characteristics, such for example as a tractor fuel of relatively high flash or initial boiling point. Thus, as shown in the drawing, one or more trays such as tray 82, preferably superposed above the point of entry of the line 79, are provided, together with a line 83 for conducting the distillate to a lower pressure stripping tower 84. The tower 84 may be equipped with a steam line 85 for introducing steam and with appropriate contact or fractionating elements to insure the desired fractionation. The stripped distillate constituting a product of the desired flash test and boiling range is withdrawn through line 86 and the vapors from the tower are passed through a line 87 to the condenser coil 62 wherein they are sub-

jected to condensation, together with the vapors from the tower 54.

In practicing the invention gas oil or a mixture of gas oil and naphtha is subjected to cracking in the high cracking per pass coil 66 at temperatures such as 900° F. to 1050° F., under relatively high pressures, such as 400 to 1000 pounds, under conditions of 15% to 35% cracking per pass (as measured by conversion into 400° F. endpoint gasoline); the reduced crude is heated to temperatures of about 880° F. to 925° F. in the heating coil 31 to maintain the desired coking conditions in the coking drum 33 wherein coking is carried on under relatively low pressure, such as 50 pounds or lower, and the heavy gas oil is subjected to cracking in the cracking coil 58 under temperatures, such as 900° F. to 950° F., at pressures, such as 200 to 400 pounds, with rates of cracking per pass of about 10% to 20%.

In an example of the invention Mid-Continent crude is preheated by heat exchange with vapors and condensate from tower 73 to a temperature of 625° F. and is then raised in heating coil 13 to a temperature of 740° F. The heated crude is subjected to distillation and fractionation in tower 18. The tower is held at 10 pounds pressure and steam is introduced into the bottom of the tower which is maintained at a temperature of 705° F. A 200° F.-350° F. endpoint naphtha distillate is taken off overhead, a heavy naphtha cut is collected on tray 21, a kerosene cut is collected on tray 22, light gas oil is collected on tray 23 and heavy gas oil is collected on tray 24. The fractionation is carried on with the aid of side stripping with steam to form a light gas oil of 650° F. endpoint and a heavy gas oil of about 800° F. endpoint. The kerosene is withdrawn as a product of the process. The heavy naphtha and light gas oil cuts are combined and, after preheating by heat exchange with distillate from tower 54 and with vapors flowing from the evaporator 70, the mixture is combined with cycle condensate withdrawn from tower 73 at a temperature of 700° F. and subjected to cracking in the heating coil 66 under 150 pounds pressure with a maximum temperature of 1010° F. and with a rate of 20-25% cracking per pass. The gasoline constituents of the stock introduced into the heating coil 66 are subjected to reforming and heavier components are converted into gasoline constituents. The stream from the cracking coil is quenched to 800-850° F. by condensate from tower 73 which is introduced to the transfer line through line 69 after being cooled as by heat exchange with crude oil charge and water. The evaporator 70 is maintained at 200 pounds pressure and is refluxed with condensate drawn from tower 73 which after being cooled is introduced through line 71. A top temperature of 750° F. and a bottom temperature of 810° F. is maintained in the evaporator 70 and the evaporator bottoms are flashed in the separating zone 40 of tower 35 which is maintained under 25 pounds pressure.

Reduced crude is connected from the crude stripping tower 18 through line 44 and is directed through line 46 into the tower 35. The reduced crude, together with reflux condensate, is withdrawn from tray 38 and passed to the heating coil 31 which is maintained at an outlet temperature of 900° F. under 50 pounds pressure. The heated stream from coil 31 passes into the coking drum 33 maintained under 50 pounds pressure with a top temperature of 820° F. and the heated products are converted to a coke residue. The vapors

from the coking operation are fractionated in tower 35 together with the flashed vapors from the high cracking per pass cracking operation as well as with vapors from the heavy gas oil cracking operation. A temperature of 785° F. is maintained adjacent the tray 38 and with steam being introduced into the tray the reflux condensate that collects with the reduced crude for passage into the heating coil 31 consists essentially of constituents boiling above 800° F. The temperature at the bottom of the separating zone 40 is maintained at about 750° F., a portion of the bottoms being passed through a cooling coil and thence back into the separating zone, while fuel oil is withdrawn through line 41 as a product of the process. Heavy gas oil of 800° F. endpoint from the crude stripping operation is directed through line 57 into the tower 54. Steam is introduced at the bottom of the tower and a reflux condensate is collected therein at a temperature of 650° F. The heavy gas oil having an initial boiling point of about 650° F. and an endpoint of about 850° F. is directed to the heavy gas oil cracking coil 58 in which it is subjected to cracking with a maximum temperature of 950° F. under 400 pounds pressure with a cracking per pass of about 12% and the cracked products are discharged into the separating zone 40 of tower 45.

The overhead distillate from tower 54 includes light gas oil and naphtha. This distillate is withdrawn from gas separator 63 and after being passed in heat exchange with the vapors flowing from tower 54 to condenser 62, is refluxed on the tower 73 so that lighter constituents thereof may pass overhead as distillate from the tower while heavier constituents are combined with the cycle condensate passing to the cracking coil 66. The tower 73 is maintained at 200 pounds pressure with a top temperature of 435° F. Intermediate fractions are withdrawn from tray 82 and subjected to refractionation in tower 84 to produce a tractor oil which is withdrawn as a product of the process through line 86 while the vapors pass through line 87 and are condensed in the condenser 62 together with the vapors from tower 54. The overhead vapors from the tower 73 are condensed in condenser 74 and collected in gas separator 75 under normal temperatures as desired gasoline distillate.

In a second example of the invention, a Mid-Continent crude is preheated by heat exchange with vapors and condensate from tower 73 to a temperature of 660° F. and the preheated crude is passed directly into the tower 18 for distillation and fractionation. The tower is operated at 10 pounds pressure with steam being introduced into the bottom of the tower wherein a temperature of 625° F. is maintained. The fractionation is carried on in the tower to produce the same character of products as has been described in the first example, except that instead of collecting separate light gas oil and heavy gas oil cuts, only a single gas oil cut consisting essentially of light gas oil constituents is made and this gas oil is combined with the heavy naphtha cut and subjected to cracking in the heating coil 66. The crude residuum is drawn from tower 18 and directed by pump 43 through lines 44 and 45 to the heating coil 13 wherein it is heated to a temperature of 750° F. to 800° F. and the heated residue is then passed to transfer line 15 and through lines 17 and 46 to the tower 35. The operation is otherwise carried on in a manner similar to that of the first example.

In the specification and claims wherein reference is made to end points or distilling ranges of products involving temperatures of about 800° F. and higher, it is to be understood that the temperatures given are determined by vacuum distillation and interpolated to an atmospheric pressure basis.

In some cases, particularly when it is desired to withdraw relatively large portions of fractions, such as kerosene and gas oil, from the crude oil stripper as a product or products of the process, extraneous charging stock is introduced into the system to maintain gasoline producing capacity. Thus extraneous gas oil is charged to the cracking coil 66 or is introduced into either or both of the fractionators 73 and 54.

While we have described a particular embodiment of our invention for purposes of illustration, it is to be understood that the invention is not restricted thereto and that various modifications and adaptations thereof may be made within the spirit of the invention.

We claim:

1. In the cracking of hydrocarbons the process that comprises subjecting residual constituents of crude petroleum to coking temperature to effect conversion into coke residue, subjecting resultant evolved vapors to fractionation in a fractionating zone to form a heavy condensate and a lighter fraction comprising intermediate constituents higher boiling than gasoline, subjecting resultant cracked products into a low pressure separating zone wherein separation of vapors from liquid residue takes place, passing resultant separated vapors into aforesaid fractionating zone and subjecting said vapors to fractionation therein together with vapors from the coking operation so that intermediate constituents produced in the cracking of said condensate enter into and constitute a part of aforesaid lighter fraction, subjecting oil to cracking temperature under superatmospheric pressure in a separate cracking zone under conditions of relatively high cracking per pass to effect conversion into gasoline of high anti-knock quality, separating resultant cracked products into vapors and residue in a higher pressure separating zone, directing said liquid residue into said low pressure separating zone wherein the residue is subjected to flashing in contact with products introduced from the heavy condensate cracking zone, passing separated vapors from the higher pressure separating zone into a separate fractionating zone wherein the vapors are fractionated to form a desired distillate and higher boiling reflux condensate, directing the aforesaid lighter fraction comprising intermediate constituents to the latter fractionating zone so that intermediate constituents thereof enter into and constitute a part of said reflux condensate formed therein, and directing such higher boiling reflux condensate to the last-named cracking zone.

2. In the cracking of hydrocarbons the process that comprises subjecting residual constituents of crude petroleum to coking temperature to effect conversion into coke residue, subjecting resultant evolved vapors to fractionation in a fractionating zone to form a heavy condensate and a lighter fraction comprising intermediate constituents higher boiling than gasoline, subjecting said heavy condensate to cracking tem-

perature to effect conversion into intermediate constituents higher boiling than gasoline, directing resultant cracked products into a low pressure separating zone wherein separation of vapors from liquid residue takes place, passing resultant separated vapors into aforesaid fractionating zone and subjecting said vapors to fractionation therein together with vapors from the coking operation so that intermediate constituents produced in the cracking of said condensate enter into and constitute a part of the aforesaid lighter fraction, subjecting oil to cracking temperature under superatmospheric pressure in a separate cracking zone under conditions of relatively high cracking per pass to effect conversion into gasoline of high anti-knock quality, separating resultant cracked products into vapors and residue in a higher pressure separating zone, dephlegmating the separated vapors therein to effect condensation of heavier constituents of the vapors, passing the dephlegmated vapors into a separate fractionating zone wherein the vapors are fractionated to form a desired distillate and a higher boiling reflux condensate, directing said liquid residue from the higher pressure separating zone to said low pressure separating zone wherein the residue is subjected to flashing in contact with products introduced from the heavy condensate cracking zone, directing the aforesaid lighter fraction comprising intermediate constituents to the latter fractionating zone so that intermediate constituents thereof enter into and constitute a part of said reflux condensate formed therein, and directing such higher boiling reflux condensate to the last-named cracking zone.

3. In the cracking of hydrocarbons the process that comprises introducing crude petroleum residue into a primary fractionating zone in contact with hot vapors therein, maintaining such conditions of temperature and pressure therein as to effect reflux condensation of heavy constituents boiling in excess of 800° F. and form a resultant mixture of crude petroleum residue and heavy reflux condensate, introducing a stripping medium into said mixture to effect removal of the lower boiling components thereof and produce a stripped mixture having an initial boiling point of upwards of about 800° F., withdrawing the stripped mixture of crude petroleum residue and heavy reflux condensate and directing the mixture to a coking zone wherein the mixture is subjected to a coking temperature to effect conversion into coke residue, restricting the recycling of condensate to the coking zone to said heavy fraction, passing resultant evolved vapors from the coking zone to said primary fractionating zone, passing the uncondensed vapors from the primary fractionating zone to a secondary fractionating zone wherein the vapors are subjected to fractionation under such conditions of temperature and pressure as to form a heavy condensate comprising constituents boiling within a range of the order of 650° F.-800° F. and a lighter fraction comprising intermediate constituents higher boiling than gasoline, introducing a stripping medium into said heavy condensate to effect removal of the lower boiling components thereof and produce a stripped condensate having an initial boiling point of the order of 650° F.-700° F., subjecting said stripped heavy condensate to cracking temperature to effect conversion into intermediate constituents higher boiling than gasoline, directing resultant cracked products into a separating

zone wherein separation of vapors from liquid residue takes place, withdrawing said liquid residue as a product of the process, passing resultant separated vapors to said primary fractionating zone so that said vapors are fractionated in the primary and secondary fractionating zones and intermediate constituents formed in the cracking of said heavy condensate are combined with aforesaid intermediate constituents from the coking operation, subjecting oil to cracking temperature in a separate cracking zone under conditions of relatively high cracking per pass to effect conversion into gasoline constituents of high anti-knock quality, separating resultant cracked products into vapors and liquid residue in a separate separating zone, passing separated vapors into a separate fractionating zone wherein the vapors are subjected to fractionation to form reflux condensate and a desired lighter distillate, directing the aforesaid lighter fraction comprising aforesaid intermediate constituents into the latter fractionating zone so that such intermediate constituents are combined with reflux condensate therein and directing said reflux condensate to the last-named cracking zone.

4. In the cracking of hydrocarbons the process that comprises introducing crude petroleum residue into a primary fractionating zone in contact with hot vapors therein, maintaining such conditions of temperature and pressure therein as to effect reflux condensation of heavy constituents boiling in excess of 800° F. and form a resultant mixture of crude petroleum residue and heavy reflux condensate, introducing a stripping medium into said mixture to effect removal of the lower boiling components thereof and produce a stripped mixture having an initial boiling point of upwards of about 800° F., withdrawing the stripped mixture of crude petroleum residue and heavy reflux condensate and passing the mixture through a heated passageway of restricted cross sectional area wherein it is subjected to a cracking temperature, passing the hot products from the heated passageway into an enlarged coking zone wherein the products are maintained at a coking temperature to effect conversion into coke residue, restricting the recycling of condensate to the coking zone to said heavy fraction, passing resultant evolved vapors from the coking zone to said primary fractionating zone, passing the uncondensed vapors from the primary fractionating zone to a secondary fractionating zone wherein the vapors are subjected to fractionation under such conditions of temperature and pressure as to form a heavy condensate comprising constituents boiling within a range of the order of 650° F.-800° F. and a lighter fraction comprising intermediate constituents higher boiling than gasoline, subjecting said stripped heavy condensate to cracking temperature to effect conversion into intermediate constituents higher boiling than gasoline, directing resultant cracked products into a separating zone wherein separation of vapors from liquid residue takes place, preventing the return of any of said liquid residue to the coking zone and withdrawing said liquid residue as a product of the process, passing resultant separated vapors to said primary fractionating zone so that said vapors are fractionated in the primary and secondary fractionating zones and intermediate constituents formed in the cracking of said heavy condensate are combined with aforesaid intermediate constituents from the coking operation,

subjecting intermediate constituents so combined to cracking temperature in a separate cracking zone under conditions of relatively high cracking per pass to effect conversion into gasoline constituents of high anti-knock quality, separating resultant cracked products into vapors and liquid residue in a separate separating zone, preventing the return of any of said liquid residue to the coking zone and withdrawing said liquid residue as a product of the process, and passing the separated vapors into a separate fractionating zone wherein the vapors are subjected to fractionation to recover a desired gasoline product.

5 5. In the cracking of hydrocarbons the process that comprises introducing crude petroleum residue into a primary fractionating zone in contact with hot vapors therein, withdrawing a resultant mixture of crude petroleum residue and heavy condensed constituents and directing the mixture to a coking zone wherein the mixture is subjected to a coking temperature to effect conversion into coke residue, passing resultant evolved vapors to said primary fractionating zone, passing vapors from the primary fractionating zone to a secondary fractionating zone wherein the vapors are subjected to fractionation to form a heavy condensate and a lighter fraction comprising intermediate constituents higher boiling than gasoline, subjecting said heavy condensate to cracking temperature to effect conversion into intermediate constituents higher boiling than gasoline, directing resultant cracked products into a low pressure separating zone

20 wherein separation of vapors from liquid residue takes place, passing resultant separated vapors to said primary fractionating zone so that said vapors are fractionated in the primary and secondary fractionating zones and intermediate constituents formed in the cracking of said heavy condensate are combined with aforesaid intermediate constituents from the coking operation, subjecting oil to cracking temperature under superatmospheric pressure in a separate cracking zone under conditions of relatively high cracking per pass to effect conversion into gasoline of high anti-knock quality, separating resultant cracked products into vapors and residue in a higher pressure separating zone, directing said liquid residue into said low pressure separating zone wherein the residue is subjected to flashing in contact with products introduced from the heavy condensate cracking zone, withdrawing a liquid residue from the low pressure separating zone as a product of the process, passing separated vapors from the higher pressure separating zone into a separate fractionating zone wherein the vapors are fractionated to form a desired distillate and higher boiling reflux condensate, directing the aforesaid lighter fraction comprising intermediate constituents to the latter fractionating zone so that intermediate constituents thereof enter into and constitute a part of said reflux condensate formed therein, and directing such higher boiling reflux condensate to the last-named cracking zone.

25 6. In the cracking of hydrocarbons the process that comprises introducing crude petroleum residue into a primary fractionating zone in contact with hot vapors therein, maintaining such conditions of temperature and pressure therein as to effect condensation of a heavy fraction consisting essentially of constituents boiling in excess of 800° F., withdrawing the resultant mixture of crude petroleum residue and condensed heavy

30 35 40 45 50 55 60 65 70 75

cracking zone under conditions of relatively high cracking per pass to effect conversion into gasoline of high anti-knock quality, separating resultant cracked products into vapors and residue in a higher pressure separating zone, directing said liquid residue into said low pressure separating zone wherein the residue is subjected to flashing in contact with products introduced from the heavy condensate cracking zone, withdrawing a liquid residue from the low pressure separating zone as a product of the process, passing separated vapors from the higher pressure separating zone into a separate fractionating zone wherein the vapors are fractionated to form a desired distillate and higher boiling reflux condensate, directing the aforesaid lighter fraction comprising intermediate constituents to the latter fractionating zone so that intermediate constituents thereof enter into and constitute a part of said reflux condensate formed therein, and directing such higher boiling reflux condensate to the last-named cracking zone.

6. In the cracking of hydrocarbons the process that comprises introducing crude petroleum residue into a primary fractionating zone in contact with hot vapors therein, maintaining such conditions of temperature and pressure therein as to effect condensation of a heavy fraction consisting essentially of constituents boiling in excess of 800° F., withdrawing the resultant mixture of crude petroleum residue and condensed heavy

cracking zone under conditions of relatively high cracking per pass to effect conversion into gasoline of high anti-knock quality, separating resultant cracked products into vapors and residue in a higher pressure separating zone, directing said liquid residue into said low pressure separating zone wherein the residue is subjected to flashing in contact with products introduced from the heavy condensate cracking zone, withdrawing a liquid residue from the low pressure separating zone as a product of the process, passing separated vapors from the higher pressure separating zone into a separate fractionating zone wherein the vapors are fractionated to form a desired distillate and higher boiling reflux condensate, directing the aforesaid lighter fraction comprising intermediate constituents to the latter fractionating zone so that intermediate constituents thereof enter into and constitute a part of said reflux condensate formed therein, and directing such higher boiling reflux condensate to the last-named cracking zone.

6. In the cracking of hydrocarbons the process that comprises introducing crude petroleum residue into a primary fractionating zone in contact with hot vapors therein, maintaining such conditions of temperature and pressure therein as to effect condensation of a heavy fraction consisting essentially of constituents boiling in excess of 800° F., withdrawing the resultant mixture of crude petroleum residue and condensed heavy

cracking zone under conditions of relatively high cracking per pass to effect conversion into gasoline of high anti-knock quality, separating resultant cracked products into vapors and residue in a higher pressure separating zone, directing said liquid residue into said low pressure separating zone wherein the residue is subjected to flashing in contact with products introduced from the heavy condensate cracking zone, withdrawing a liquid residue from the low pressure separating zone as a product of the process, passing separated vapors from the higher pressure separating zone into a separate fractionating zone wherein the vapors are fractionated to form a desired distillate and higher boiling reflux condensate, directing the aforesaid lighter fraction comprising intermediate constituents to the latter fractionating zone so that intermediate constituents thereof enter into and constitute a part of said reflux condensate formed therein, and directing such higher boiling reflux condensate to the last-named cracking zone.

6. In the cracking of hydrocarbons the process that comprises introducing crude petroleum residue into a primary fractionating zone in contact with hot vapors therein, maintaining such conditions of temperature and pressure therein as to effect condensation of a heavy fraction consisting essentially of constituents boiling in excess of 800° F., withdrawing the resultant mixture of crude petroleum residue and condensed heavy

fraction and directing the mixture to a coking zone wherein the mixture is subjected to a coking temperature to effect conversion into coke residue, restricting the recycling of condensate to the coking zone to said heavy fraction, passing resultant evolved vapors from the coking zone to said primary fractionating zone, passing the uncondensed vapors from the primary fractionating zone to a secondary fractionating zone wherein the vapors are subjected to fractionation to form a heavy condensate having an initial boiling point of about 650° F.-700° F. and an end point of about 800° F. and a lighter fraction comprising intermediate constituents higher boiling than gasoline, subjecting said heavy condensate to cracking temperature to effect conversion into intermediate constituents higher boiling than gasoline, directing resultant cracked products into a separating zone wherein separation of vapors from liquid residue takes place, withdrawing said liquid residue as a product of the process, passing resultant separated vapors to said primary fractionating zone so that said vapors are fractionated in the primary and secondary fractionating zones and intermediate constituents formed in the cracking of said heavy condensate are combined with aforesaid intermediate constituents from the coking operation, subjecting oil to cracking temperature in a separate cracking zone under conditions of relatively high cracking per pass to effect conversion into gasoline constituents of high anti-knock quality, separating resultant cracked products into vapors and liquid residue in a separate separating zone, passing separated vapors into a separate fractionating zone wherein the vapors are subjected to fractionation to form reflux condensate and a desired lighter distillate, directing the aforesaid lighter fraction comprising aforesaid intermediate constituents into the latter fractionating zone so that such intermediate constituents are combined with reflux condensate therein and directing said reflux condensate to the last-named cracking zone.

7. In the cracking of hydrocarbons the process that comprises introducing crude petroleum residue into a primary fractionating zone in contact with hot vapors therein, maintaining such conditions of temperature and pressure therein as to effect condensation of a heavy fraction consisting essentially of constituents boiling in excess of 800° F., withdrawing the resultant mixture of crude petroleum residue and condensed heavy fraction and directing the mixture to a coking zone wherein the mixture is subjected to a coking temperature to effect conversion into coke residue, restricting the recycling of condensate to the coking zone to said heavy fraction, passing resultant evolved vapors from the coking zone to said primary fractionating zone, passing the uncondensed vapors from the primary fractionating zone to a secondary fractionating zone wherein the vapors are subjected to fractionation under such conditions of temperature and pressure as to form a heavy condensate consisting essentially of constituents boiling within the range of 650° F.-800° F. and a lighter fraction comprising intermediate constituents higher boiling than gasoline, subjecting said heavy condensate to cracking temperature to effect conversion into intermediate constituents higher boiling than gasoline, directing resultant cracked products into a separating zone wherein separation of vapors from liquid residue takes place, withdrawing said liquid residue as a product of

the process, passing resultant separated vapors to said primary fractionating zone so that said vapors are fractionated in the primary and secondary fractionating zones and intermediate constituents formed in the cracking of said heavy condensate are combined with aforesaid intermediate constituents from the coking operation, subjecting oil to cracking temperature in a separate cracking zone under conditions of relatively high cracking per pass to effect conversion into gasoline constituents of high anti-knock quality, separating resultant cracked products into vapors and liquid residue in a separate separating zone, passing separated vapors into a separate fractionating zone wherein the vapors are subjected to fractionation to form reflux condensate and a desired lighter distillate, directing the aforesaid lighter fraction comprising aforesaid intermediate constituents into the latter fractionating zone so that such intermediate constituents are combined with reflux condensate therein and directing said reflux condensate to the last-named cracking zone.

8. In the cracking of hydrocarbons the process that comprises subjecting residual constituents of crude petroleum to coking temperature to effect conversion into coke residue, passing resultant evolved vapors to a primary fractionating zone wherein the vapors are subjected to fractionation under such conditions of temperature and pressure as to effect condensation of a heavy fraction consisting essentially of constituents boiling in excess of 800° F., cycling said heavy fraction to the coking zone wherein it is heated at a cracking temperature and subjected to cracking and coking with said residual constituents of the crude petroleum, restricting the recycling of condensate to the coking zone to said heavy fraction, passing the uncondensed vapors from the primary fractionating zone to a secondary fractionating zone wherein the vapors are subjected to fractionation under such conditions of temperature and pressure as to form a heavy condensate consisting essentially of constituents boiling within the range of 650° F.-800° F. and a lighter fraction comprising intermediate constituents higher boiling than gasoline, subjecting said heavy condensate to cracking temperature to effect conversion into intermediate constituents higher boiling than gasoline, directing resultant cracked products into a separating zone wherein separation of vapors from liquid residue takes place, preventing the return of any of said liquid residue to the coking zone and withdrawing said liquid residue as a product of the process, passing resultant separated vapors to said primary fractionating zone so that said vapors are fractionated in the primary and secondary fractionating zones and intermediate constituents formed in the cracking of said heavy condensate are combined with aforesaid intermediate constituents from the coking operation, subjecting intermediate constituents so combined to cracking temperature in a separate cracking zone under conditions of relatively high cracking per pass to effect conversion into gasoline constituents of high anti-knock quality, separating resultant cracked products into vapors and liquid residue in a separate separating zone, preventing the return of any of said liquid residue to the coking zone and withdrawing said liquid residue as a product of the process, and passing the separated vapors into a separate fractionating zone wherein the vapors are subjected to fractionation to recover a desired gasoline product.

9. In the cracking of hydrocarbons the process that comprises introducing crude petroleum residue into a primary fractionating zone in contact with hot vapors therein, maintaining such conditions of temperature and pressure therein as to effect condensation of a heavy fraction consisting essentially of constituents boiling in excess of 800° F., withdrawing the resultant mixture of crude petroleum residue and condensed heavy fraction and directing the mixture to a coking zone where the mixture is subjected to a coking temperature to effect conversion into coke residue, restricting the recycling of condensate to the coking zone to said heavy fraction, passing resultant evolved vapors from the coking zone to said primary fractionating zone, passing the uncondensed vapors from the primary fractionating zone to a secondary fractionating zone wherein the vapors are subjected to fractionation under such conditions of temperature and pressure as to form a heavy condensate consisting essentially of constituents boiling within the range of 650° F.-800° F. and a lighter fraction comprising intermediate constituents higher boiling than gasoline, subjecting said heavier condensate to cracking temperature to effect conversion into intermediate constituents higher boiling than gasoline, directing resultant cracked products into a separating zone wherein separation of vapors from liquid residue takes place, preventing the return of any of said liquid residue to the coking zone and withdrawing said liquid residue as a product of the process, passing resultant separated vapors to said primary fractionating zone so that said vapors are fractionated in the primary and secondary fractionating zones and intermediate constituents formed in the cracking of said heavy condensate are combined with aforesaid intermediate constituents from the coking operation, subjecting intermediate constituents so combined to cracking temperature in a separate cracking zone under conditions of relatively high cracking per pass to effect conversion into gasoline constituents of high anti-knock quality, separating resultant cracked products into vapors and liquid residue in a separate separating zone, preventing the return of any of said liquid residue to the coking zone and withdrawing said liquid residue as a product of the process, and passing the separated vapors into a separate fractionating zone wherein the vapors are subjected to fractionation to recover a desired gasoline product.

10. In the cracking of hydrocarbons the process that comprises introducing crude petroleum residue into a primary fractionating zone in contact with hot vapors therein, maintaining such conditions of temperature and pressure therein as to effect condensation of a heavy fraction consisting essentially of constituents boiling in excess of 800° F., withdrawing the resultant mixture of crude petroleum residue and condensed heavy fraction and directing the mixture to a coking zone wherein the mixture is subjected to a coking temperature to effect conversion into coke residue, restricting the recycling of condensate to the coking zone to said heavy fraction, passing resultant evolved vapors from the coking zone to said primary fractionating zone, passing the uncondensed vapors from the primary fractionating zone to a secondary fractionating zone wherein the vapors are subjected to fractionation to form a heavy condensate having an initial boiling point of about 650° F.-700° F. and an end point of about 800° F. and a lighter frac-

tion comprising intermediate constituents higher boiling than gasoline, subjecting said heavy condensate to cracking temperature to effect conversion into intermediate constituents higher boiling than gasoline, directing resultant cracked products into a separating zone wherein separation of vapors from liquid residue takes place, preventing the return of any of said liquid residue to the coking zone and withdrawing said liquid residue as a product of the process, passing resultant separated vapors to said primary fractionating zone so that said vapors are fractionated in the primary and secondary fractionating zones and intermediate constituents formed in the cracking of said heavy condensate are combined with aforesaid intermediate constituents from the coking operation, subjecting intermediate constituents so combined to cracking temperature in a separate cracking zone under conditions of relatively high cracking per pass to effect conversion into gasoline constituents of high anti-knock quality, separating resultant cracked products into vapors and liquid residue in a separate separating zone, preventing the return of any of said liquid residue to the coking zone and withdrawing said liquid residue as a product of the process, and passing the separated vapors into a separate fractionating zone wherein the vapors are subjected to fractionation to recover a desired gasoline product.

11. In the cracking of hydrocarbons the process that comprises subjecting crude petroleum to fractionation to form a crude residue, a high boiling condensate having an end point of the order of 800° F. and a lighter fraction comprising intermediate constituents higher boiling than gasoline, introducing said crude residue into a primary fractionating zone in contact with hot vapors therein, maintaining such conditions of temperature and pressure therein as to effect condensation of a heavy fraction having an initial boiling point of the order of 800° F.-850° F., withdrawing the resultant mixture of crude petroleum residue and condensed heavy fraction and directing the mixture to a coking zone wherein the mixture is subjected to a coking temperature to effect conversion into coke residue, passing resultant evolved vapors to said primary fractionating zone, passing vapors from the primary fractionating zone to a secondary fractionating zone wherein the vapors are subjected to fractionation under such conditions of temperature and pressure as to form a heavy condensate consisting essentially of constituents boiling within the range of 650° F.-800° F. and a lighter fraction comprising intermediate constituents higher boiling than gasoline, introducing said high boiling condensate from the crude fractionation to said secondary fractionating zone, subjecting said high boiling condensate to cracking temperature to effect conversion into intermediate constituents higher boiling than gasoline, directing resultant cracked products into a separating zone wherein separation of vapors from liquid residue takes place, withdrawing said liquid residue as a product of the process, passing resultant separated vapors to said primary fractionating zone so that said vapors are fractionated in the primary and secondary fractionating zones and intermediate constituents formed in the cracking of said heavy condensate are combined with aforesaid intermediate constituents from the coking operation, subjecting intermediate constituents so combined and intermediate constituents obtained

from the crude petroleum fractionation to cracking temperature under conditions of higher cracking per pass than obtain in the cracking of the aforesaid heavy condensate to effect conversion into gasoline constituents of high anti-knock quality, and separately fractionating the resultant cracked products to recover a desired gasoline product.

12. In the cracking of hydrocarbons the process that comprises heating crude petroleum and separating it into vapors and residue, subjecting the vapors to fractionation to form a fraction comprising intermediate constituents higher boiling than gasoline, introducing said crude residue into a primary fractionating zone in contact with hot vapors therein, maintaining such conditions of temperature and pressure therein as to effect condensation of a heavy fraction consisting essentially of constituents boiling in excess of 800° F., withdrawing the resultant mixture of crude petroleum residue and condensed heavy fraction and directing the mixture to a coking zone wherein the mixture is subjected to a coking temperature to effect conversion into coke residue, passing resultant evolved vapors to said primary fractionating zone, passing vapors from the primary fractionating zone to a secondary fractionating zone wherein the vapors are subjected to fractionation under such conditions of temperature and pressure as to form a heavy condensate consisting essentially of constituents boiling within the range of 650° F.-800° F. and a lighter fraction comprising intermediate constituents higher boiling than gasoline, subjecting said heavy condensate to cracking temperature to effect conversion into intermediate constituents higher boiling than gasoline, directing resultant cracked products into a separating zone wherein separation of vapors from liquid residue takes place, preventing the return of any of said liquid residue to the coking zone and withdrawing said liquid residue as a product of the process, passing resultant separated vapors to said primary fractionating zone so that said vapors are fractionated in the primary and secondary fractionating zones and intermediate constituents formed in the cracking of said heavy condensate are combined with aforesaid intermediate constituents from the coking operation, subjecting intermediate constituents so combined and intermediate constituents obtained from the crude petroleum fractionation to cracking temperature under conditions of higher cracking per pass than obtain in the cracking of the aforesaid heavy condensate to effect conversion into gasoline constituents of high anti-knock quality, separating resultant cracked products into vapors and liquid residue in a separate separating zone, preventing the return of any of said liquid residue to the coking zone and withdrawing said liquid residue as a product of the process, and passing the separated vapors into a separate fractionating zone wherein the vapors are subjected to fractionation to recover a desired gasoline product.

13. In the cracking of hydrocarbons the process that comprises heating crude petroleum and separating it into vapors and residue, subjecting the vapors to fractionation to form a fraction comprising intermediate constituents higher boiling than gasoline, introducing said crude residue into a primary fractionating zone in contact with hot vapors therein, withdrawing a resultant mixture of crude petroleum residue and heavy condensed constituents and directing the mixture to

a coking zone wherein the mixture is subjected to a coking temperature to effect conversion into coke residue, passing resultant evolved vapors to said primary fractionating zone, passing vapors from the primary fractionating zone to a secondary fractionating zone wherein the vapors are subjected to fractionation to form a heavy condensate and a lighter fraction comprising intermediate constituents higher boiling than gasoline, subjecting said heavy condensate to cracking temperature to effect conversion into intermediate constituents higher boiling than gasoline, directing resultant cracked products into a separating zone wherein separation of vapors from liquid residue takes place, withdrawing said liquid residue as a product of the process, passing resultant separated vapors to said primary fractionating zone so that said vapors are fractionated in the primary and secondary fractionating zones and intermediate constituents formed in the cracking of said heavy condensate are combined with aforesaid intermediate constituents from the coking operation, subjecting aforesaid fraction comprising intermediate constituents higher boiling than gasoline obtained from the crude petroleum to cracking temperature in a separate cracking zone under conditions of relatively high cracking per pass to effect conversion into gasoline constituents of high anti-knock quality, separating resultant cracked products into vapors and liquid residue in a separate separating zone, passing separated vapors into a separate fractionating zone wherein the vapors are subjected to fractionation to form reflux condensate and a desired lighter distillate, directing the aforesaid lighter fraction comprising aforesaid intermediate constituents into the latter fractionating zone so that such intermediate constituents are combined with reflux condensate therein and directing said reflux condensate to the last-named cracking zone.

14. In the cracking of hydrocarbons the process that comprises heating crude petroleum and separating it into vapors and residue, subjecting the vapors to fractionation to form a fraction comprising intermediate constituents higher boiling than gasoline, introducing said crude residue into a primary fractionating zone in contact with hot vapors therein, withdrawing a resultant mixture of crude petroleum residue and heavy condensed constituents and directing the mixture to a coking zone wherein the mixture is subjected to a coking temperature to effect conversion into coke residue, passing resultant evolved vapors to said primary fractionating zone, passing vapors from the primary fractionating zone to a secondary fractionating zone wherein the vapors are subjected to fractionation to form a heavy condensate and a lighter fraction comprising intermediate constituents higher boiling than gasoline, subjecting said heavy condensate to cracking temperature to effect conversion into intermediate constituents higher boiling than gasoline, directing resultant cracked products into a low pressure separating zone wherein separation of vapors from liquid residue takes place, passing resultant separated vapors to said primary fractionating zone so that said vapors are fractionated in the primary and secondary fractionating zones and intermediate constituents formed in the cracking of said heavy condensate are combined with aforesaid intermediate constituents from the coking operation, subjecting aforesaid fraction comprising intermediate constituents higher boiling than gaso-

line obtained from the crude petroleum to cracking temperature in a separate cracking zone under conditions of relatively high cracking per pass to effect conversion into gasoline constituents of high anti-knock quality, separating resultant cracked products into vapors and residue in a higher pressure separating zone, directing said liquid residue into said low pressure separating zone wherein the residue is subjected to flashing in contact with products introduced from the heavy condensate cracking zone, passing separated vapors from the higher pressure separating zone into a separate fractionating zone wherein the vapors are fractionated to form a desired distillate and higher boiling reflux condensate, directing the aforesaid lighter fraction comprising intermediate constituents to the latter fractionating zone so that intermediate constituents thereof enter into and constitute a part of said reflux condensate formed therein, and directing such higher boiling reflux condensate to the last-named cracking zone.

15. In the cracking of hydrocarbons the process that comprises separately distilling crude petroleum to separate residual constituents from intermediate constituents higher boiling than gasoline, subjecting such residual constituents to coking temperature to effect conversion into coke residue, passing resultant evolved vapors to a primary fractionating zone wherein the vapors are subjected to fractionation under such conditions of temperature and pressure as to effect condensation of a heavy fraction consisting essentially of constituents boiling in excess of 800° F., cycling said heavy fraction to the coking zone wherein it is heated at a cracking temperature and subjected to cracking and coking with said residual constituents of the crude petroleum, restricting the recycling of condensate to the cok-

ing zone to said heavy fraction, passing vapors from the primary fractionating zone to a secondary fractionating zone wherein the vapors are subjected to fractionation under such conditions of temperature and pressure as to separate a heavy condensate consisting essentially of constituents boiling within the range of 650° F.-800° F. from a lighter fraction comprising intermediate constituents higher boiling than gasoline, subjecting said heavy condensate to cracking conditions of temperature and pressure to effect conversion into intermediate constituents higher boiling than gasoline, directing resultant cracked products into a separating zone wherein separation of vapors from liquid residue takes place, combining resultant separated vapors with vapors from the coking operation for fractionation therewith so that intermediate constituents produced in the cracking of said condensate are combined with intermediate constituents from the coking operation, subjecting intermediate constituents so combined and intermediate constituents obtained from the crude petroleum distillation to cracking temperature under conditions of higher cracking per pass than obtain in the cracking of the aforesaid heavy condensate to effect conversion into gasoline constituents of high anti-knock quality, directing the resultant cracked products into a second separating zone 30 wherein separation of vapors from liquid residue takes place, withdrawing said liquid residue to segregate it for the production of fuel oil, and passing separated vapors from said separating zone to a second fractionating zone wherein the 35 vapors are fractionated to recover a desired gasoline product.
